BY

Barney S. Glavin
ATTORNEY

UNITED STATES PATENT OFFICE.

GEORGE IRVING GILCHREST, OF DERRY, PENNSYLVANIA, ASSIGNOR TO WESTINGHOUSE ELECTRIC & MANUFACTURING COMPANY, A CORPORATION OF PENNSYLVANIA.

INSULATOR.

Application filed September 16, 1922. Serial No. 588,525.

My invention relates to insulators and particularly to suspension insulators adapted for high-potential circuits.

One object of my invention is to provide a device of the above-indicated character that shall materially increase the voltage values that it is adapted to support over those of an insulator of a similar type heretofore employed.

10 Another object of my invention is to provide a high-potential suspension insulator of such construction and that shall be so provided with a novel tension or terminal member as to greatly improve the insulating characteristics thereof.

20 A further object of my invention is to provide a high potential suspension insulator that shall be simple and durable in construction, economical in manufacture and effective in its operation.

Copending application Serial No. 589,088, filed Sept. 19, 1922, by F. H. Miller and assigned to the Westinghouse Electric & Manufacturing Company sets forth the 25 development of high-potential insulators up to an insulator similar to that for which my invention is adapted.

Heretofore, while it has been customary to employ insulating materials such as wood for the pins of insulators of the rigid cross-arm type, insulating material has not, to the best of my knowledge, ever been employed in the pins to alone sustain the load in suspension insulators of the type to which 35 my invention appertains, prior to the suggestion set forth in the above-entitled copending application.

With the advent of suspension insulators of the cap-and-pin type having a much longer body than heretofore employed or, in other words, a much greater distance between the cap and the farthest end of the pin, the idea of constructing the pin or tension member of insulating material was conceived. This construction greatly reduces the amount of metal in the insulator and, as a result, materially increases its insulating properties.

50 My invention, which is suggested as an improvement over the insulator of the above-entitled copending application, comprises a

novel tension member or pin which is so constructed of telescoped or superimposed tubes of different insulating materials as to provide a rigid structure that is prevented from 55 deterioration by moisture and charring.

The single figure of the accompanying drawing is a side view, partially in side elevation and partially in longitudinal section, of an insulator embodying my invention.

60 The device comprises in general a main insulating body member 2, preferably of porcelain, a tension member 3, metal terminal members 4 and 5 and an anchor member 6 for the inner member of the tension member 65 3.

The main insulating body member 2, preferably constructed of refractory insulating material such as porcelain or glass, is of substantially tubular form having a closed end 70 portion 8 of substantially cup shape, intermediate petticoat or surface-creepage portions 9 and an end skirt 10. The terminal member 4 having an eye or clevis thereon is of substantially cup shape closely conforming to the end portion 8 of the insulating member 2 and is preferably cemented to the portion 8 in accordance with established practice.

75 The tension structure 3, of which the anchor member 6 and the terminal member 5 constitute parts, further comprises a tubular member 11, preferably of fibrous insulating material impregnated with a binder, that is rigidly secured to the adjacent ends 12 and 80 13 of the members 5 and 6, respectively, as by threading, over which a tube 15 of refractory insulating material, such as porcelain or glass, is secured. While normally the insulating tube 11 may be adapted to sustain the 85 entire mechanical load, it may be reinforced by a member 14 of wood or other suitable material which also constitutes a filler for the tube 11.

In the above-described construction of the 90 tension member 3, sufficient mechanical strength is provided, charring from corona and deterioration by atmospheric moisture are prevented and, by the elimination of metal, the operating characteristics of the 95 100 insulator are greatly improved.

While I have shown and described a par-

22
ticular form of my invention, various modifications and changes may be made therein without departing from the spirit and scope of the invention, as set forth in the appended 5 claims.

I claim as my invention:

1. In combination, in an insulator, a member of refractory insulating material having a portion of substantially cup-shape, a pin structure embodying an elongated fibrous insulating tube and metal end members, one of which is secured in position in the cup and a body of refractory material enclosing said tube. 10
2. In combination, in an insulator, a member of refractory insulating material having a portion of substantially cup-shape, a pin structure embodying an elongated fibrous insulating tube, metal end members for said tube and an insulating filler material in the tube, one of said metal end members being secured in position in the cup and a body of refractory material enclosing said tube. 15
3. In combination, in an insulator, a member of refractory insulating material having a portion of substantially cup-shape, a pin structure embodying an elongated insulating tube, metal end members for said tube and a protective covering on said tube, one of said metal end members being disposed 20 in the cup removed from the side walls thereof, and a body of cement in the space 25 between the cup and the end member in the

cup securing the pin to said refractory member. 35

4. In combination, in an insulator, a member of refractory insulating material having a portion of substantially cup-shape, a pin structure embodying an elongated insulating tube, metal end members for said tube 40 and a refractory tube enclosing said tube, one of said metal end members being secured in position in the cup.

5. In combination, in an insulator, a member of refractory insulating material having a portion of substantially cup-shape, a pin structure embodying an elongated insulating tube and metal end members for said tube, an insulating filler material in the tube 45 and a refractory tube enclosing said tube, one of said metal members being secured in position in the cup. 50

6. In combination, in a high-voltage suspension insulator, a member of refractory insulating material having a portion of substantially cup-shape, a tension pin structure embodying an elongated fibrous load-supporting tube, metal end members for said tube, an insulating filler material in the tube and a refractory tube enclosing said 55 tube, one of said metal end members being secured in position in the cup. 60

In testimony whereof, I have hereunto subscribed my name this 6th day of September, 1922.

GEORGE IRVING GILCHREST.
